UNITED STATES PATENT OFFICE.

JEROME B. SECOR, OF DERBY, CONNECTICUT.

TYPE-WRITING MACHINE.

938,439.

Specification of Letters Patent.

Patented Oct. 26, 1909.

Application filed July 28, 1908. Serial No. 445,700.

To all whom it may concern:

Be it known that I, JEROME B. SECOR, a citizen of the United States, and resident of Derby, in the county of New Haven and State of Connecticut, have invented certain new and useful Improvements in Type-Writing Machines, of which the following is a specification.

My invention relates in general to type-writing machines, and more particularly to an improved device for bringing the type into proper printing position.

In my prior patent No. 786,056, granted March 28th, 1905, I have shown and described a type alining device in the form of a spherical or acorn shaped pin secured in a stationary member, which is adapted to engage in a curved perforation in each type-bar. The said patent also covers, under its broad terms, the use of a pin on each type-bar and a perforation in the stationary member. A specific form of pin on each type-bar, in combination with a perforation in the stationary member, forms the subject matter of my present improvement in the alining device. In front strike machines such as that known as the Secor machine, the type-bars are disposed with their pivots substantially in the arc of a circle and their axes projecting forward substantially horizontally. By reason of this arrangement the type-bar in the middle moves in a vertical plane passing through the printing point, whereas type-bars farther from the middle have movements in planes which become more nearly horizontal as their distance from the middle increases. Each type-bar shown in my said prior patent is provided with a curved perforation which forms with the arc of a circle in the plane of its movement, having its center at the pivot of the type-bar. It is stated in my said prior patent that the location of the perforations and the pin could be transposed, that is, with a perforation in the stationary member and a rounded or acorn shaped pin on each type-bar.

In accordance with my present invention, I employ a cylindrical pin on the type-bar, curved in the arc of a circle about the type-bar pivot, in combination with a double flaring perforation in the stationary member, *i. e.* corresponding with the total space occupied by the several curved cylindrical pins when the type-bars are in striking position. The perforation need only be double flaring

below the horizontal, in the usual form of machine, since the type-bars are pivoted in an arc below the horizontal less than a semi-circle. For convenience of manufacture, however, the perforation would of course in practice be made double flaring throughout its entire circumference. Accordingly the use of the term "double flaring" will be understood to mean double flaring either throughout the entire circumference or only through a portion of its circumference. The diameter of the pin should equal the smallest diameter of the perforation. With this construction a better engagement of the pin and perforation is obtained for different thicknesses of paper, since the engagement is constant after the full diameter of the pin has reached the small diameter of the double flaring perforation which is equal to the diameter of the pin and which is in the middle of the perforation. By reason of the cylindrical form of the pin, the type-bar is enabled to continue its motion beyond the point where its engagement first occurs, so that the accurate alinement of the type is insured for various thicknesses of paper, the arrangement being such that with the average thickness of paper on the platen, the type-bar strikes when the pin is midway between the point where its full diameter first engages the smaller diameter of the perforation and the limit of its inward movement.

My invention is applicable to numerous forms of typewriting machines, but may perhaps be best illustrated as embodied in a front strike machine such for instance as the Secor machine. Accordingly to enable those skilled in the art to understand and practice my invention, I have shown by way of example in the accompanying drawings and shall describe with reference thereto embodiments of my invention applied to a Secor machine.

In said drawings Figure 1 is a side elevation of the key-bar and type-bar movements with my improved alining device applied thereto. Fig. 2 is an enlarged detail elevation of the type-bar movement provided with my improved alining device. Fig. 3 is a further enlarged elevation of the alining pin and bushing provided with the double flaring perforation.

Referring now more specifically to said drawings, 10 indicates a key-bar suitably fulcrumed at its inner end and connected as by a bifurcated link 11 with a differential bell

crank lever 12. Said bell-crank lever pulls the U-shaped link 13 against the tension of return spring 14 and thus operates the type-bar 15 which is pivoted at 16 in the hangers 17, of well known construction. The U-shaped link 13 has a plate 13^a in which is a series of perforations for attaching the spring 14. By selecting the proper perforation the tension of the type-bar link can be accurately adjusted. The type-bar 15 is provided with a curved cylindrical pin 18 which in accordance with my invention conforms to the arc of a circle in the plane of movement of the type-bar with its center at the type-bar pivot.

19 is a frisket guide and 20 the frisket. It will be remembered that the frisket is U-shaped in the Secor machine. Mounted in the frisket guide 19 near the upper portion is 20 a hardened bushing 21 which is provided with a double flaring perforation as described above and clearly shown in Fig. 3. The platen is shown in dotted lines in Figs. 1 and 2.

25 I have described only one key-bar and type-bar movement, but of course it is understood that the machine has a full set of these members and the key-bars normally rest horizontally with their pivots substantially 20 in the arc of a circle with the alinement perforation as center. When the key-bar is depressed the type-bar is thrown backward into striking position, the curved cylindrical alining pin, which is preferably integral 35 with the bar, passing into the double flaring perforation. By reason of the peculiar form of the alining pin 18 and the perforation in the bushing 21, the engagement of these two members is the same for the outside type-

bars as for the inner type-bars, and during 40 the movement of the type-bar from the time the full diameter of the pin has first reached the small diameter of the perforation until its limit of movement, the alinement is accurately fixed. If the pin 18 had the acorn or 45 spherical shape described in my prior patent, the alinement would be just as good at the particular moment when the line of the largest diameter of the pin engages the line of the smallest diameter of the perforation, but 50 there would not be the possibility of such accurate alinement for different thicknesses of paper, as is accomplished by giving to the pin the form herein set forth.

55 I claim:

1. An alining device for typewriting machines, comprising in combination a stationary member provided with a double flaring perforation, and a curved cylindrical pin on 60 the type-bar disposed in an arc in the plane of movement with the center at the type-bar pivot and adapted to engage in the perforation of said stationary member.

2. In a typewriting machine, the combination with a plurality of substantially horizontally disposed type-bars having their pivots substantially in the arc of a circle and a curved cylindrical alining pin on each type-bar in an arc in the plane of movement with 65 its center at the type-bar pivot; of a stationary member provided with a double flaring perforation in the center of the arc of the type-bar pivots and in a common portion of 70 the paths of all of said alining pins.

JEROME B. SECOR.
